CLAIM

The ornamental design for a toner cartridge, as shown and described.

DESCRIPTION

FIG. 1 is a front, left bottom perspective view of a toner cartridge showing an embodiment of our new design; FIG. 2 is a rear, left, top perspective view thereof; FIG. 3 is a front view thereof; FIG. 4 is a rear side view thereof; FIG. 5 is a left side view thereof; FIG. 6 is a right side view thereof; FIG. 7 is a top plan view thereof; FIG. 8 is a bottom plan view thereof; FIG. 9 is an enlarged left side view thereof; FIG. 10 is an enlarged view of the portion of the toner cartridge defined by the area 10 in FIG. 1; and, FIG. 11 is an enlarged view of the portion of the toner cartridge defined by the area 11 in FIG. 2. The broken lines shown in the drawings depict portions of the toner cartridge that form no part of the claimed design. The dashed-dotted lines define the bounds of the claimed design and form no part thereof.

1 Claim, 10 Drawing Sheets
